Term of patent 14 years

Int. Cl. D10—02

U.S. CL. D10—39

FIG. 1 is a top plan view of a digital calendar watch showing my new design;

FIG. 2 is a right side elevation view of FIGS. 1 and 3, the left sides being substantially a mirror image thereto with the crown omitted;

FIG. 3 is a top plan view of another embodiment of my new design of FIG. 1 wherein the calendar and time indicator windows have been inverted; and

FIG. 4 is a bottom plan view of FIGS. 1 and 3.

I claim:

The ornamental design for a digital calendar watch, as shown and described.
